SELF-SEALING CAP FOR COLLAPSIBLE TUBES

William H. Godfrey, Pittsfield, Mass.

Application September 18, 1952, Serial No. 310,303

2 Claims. (Cl. 222—494)

This invention relates to a new and improved cap for collapsible tubes and more particularly to a self-sealing cap for collapsible tubes.

It is a principal object of the present invention to provide a cap for a collapsible tube which cap is normally resiliently retained in closed position, and which is urged into open position by pressure on the tube.

Another object of the present invention is to provide a highly improved self-sealing cap for a collapsible tube which may be reused with new tubes.

Still another object of the present invention is to provide a highly improved self-sealing cap for a collapsible tube which may be reused with new tubes.

Still another object of the present invention is to provide a cap for collapsible tubes wherein the single manipulation of pressing the tube operates to open the cap, extrude the desired amount of contents from the tube, and close the cap.

Yet another object of the present invention is to provide self-sealing caps for collapsible tubes from which foreign particles may be easily and quickly removed.

It is a further object of the present invention to provide a self-sealing cap for collapsible tubes which is simple and durable, which is effective for its intended purposes, and which can be manufactured and sold at a reasonable cost.

The invention consists in the features of construction, combinations of elements and arrangement of parts, which will be exemplified in the construction hereinafter described, and of which the scope will be indicated by the claims.

For other objects and for a better understanding of the invention, reference may be had to the following detailed description taken in connection with the accompanying drawing, in which:

Figure 1 is a perspective view of a device constructed in accordance with the present invention, showing the method of operation;

Fig. 2 is a view partly in section, taken along the line 2—2 of Fig. 1;

Fig. 3 is a sectional elevational view of the cap in closed position, and showing a collapsible tube in dotted outline;

Fig. 4 is an exploded view, showing in perspective the parts of the self-sealing cap;

Fig. 5 is a sectional elevational view of a slightly modified form of self-sealing cap, showing a collapsible tube in dotted outline;

Fig. 6 is a sectional view showing the cap of Fig. 5 in operative position;

Fig. 7 is a sectional elevational view of another slightly modified form of self-sealing cap, showing a collapsible tube in dotted outline;

Fig. 8 is a sectional view taken on the line 8—8 of Fig. 7; and

Fig. 9 is an elevational view, partly in section, of another slightly modified form of the device.

Referring now more particularly to the drawings, 10 represents a self-sealing cap which is adapted for attachment to a collapsible tube 11 for extrusion of the tube

contents 12, such as tooth paste, by manually effected pressure.

The cap 10 comprises a cylindrical member or body 13 which is preferably molded of plastic but which may be formed of any suitable material. Adjacent one end of the cylindrical member 13 are formed internal screw threads 14 for receiving the threaded neck 15 of the tube 11. Of course, the threads 14 may be of various sizes for attachment to tubes having different sized necks. Inwardly of the threaded portion 14 is formed an internal shoulder 16, which may or may not be integral with the cylindrical member 13. An annular groove 17 is formed on the inner surface 18 of the shoulder 16 for receiving one end of a tubular member 19. The tubular member 19 has its end fixedly secured in the groove 17, as by glue or other suitable means, and is preferably fabricated of rubber or other flexible resilient material.

Also having one end extending into base 18 of shoulder 16 is a resilient strip 20. The resilient strip 20 is fixedly secured in shoulder 16 intermediate cylindrical member 13 and tubular member 19, and normally curves transversely of the cylindrical member. The free end 21 of strip 20 is bent outwardly toward cylindrical member 13 to form an abutment or nub 22.

Extending transversely through cylindrical member 13, remote from the threaded portion 14 thereof, is a slot 23 which extends slightly more than half way around the cylindrical member. A closure or plate 24 extends through slot 23 and is slidable therein for opening and closing the free end of cylindrical member 13. On the inner surface of plate 24 is a projection or lug 25 which extends inwardly between nub 22 and the exterior of tubular member 19. Thus, nub 22 bears against lug 25 to urge plate 24 in closing relation with respect to cylindrical member 13 and in turn lug 25 bears against tubular member 19 to close or pinch the latter upon closing movement of plate 24, as shown in Fig. 3.

In order to open the cap 10, it is necessary to reverse the above procedure, by applying pressure to tube 11 which urges the tubular member 19 outwardly against lug 25 to open plate 24 against the pressure of strip 20. Upon removal of pressure from tube 11, it is seen that the cap will automatically reseal itself.

A slightly modified form of self-sealing cap is shown in Figs. 5 and 6, wherein a cylindrical member 30 is formed with one end closed, as at 31, and provided with an internally-threaded portion 32 adjacent the other end. The internally-threaded portion 32 is adapted to receive the threaded neck of collapsible tube 11, in the same manner as the first described form of the invention. Internally, the cylindrical member 30 is formed with a shoulder 33 which tapers toward the threaded portion 32. An opening 34 extends through the cylindrical member 30 adjacent the shoulder 33 to form an outlet for the contents of tube 11. Mounted within the cylindrical member 30 is a valve body or piston 35 which is provided with a split packing ring 36. The valve body 35 is formed with a conical surface 37 which is adapted to seat upon the tapering shoulder 33. Thus, upon sliding reciprocal movement of the valve body 35 within the cylinder 30, the aperture 34 will be opened and closed, as will its communication with the interior of tube 11. It is preferred to dispose a compression spring 38 intermediate the valve body 35 and the end wall 31 for urging the valve body 35 into closing relation with respect to aperture 34. While it is appreciated that an air cushion could be formed by cylindrical member 30, end wall 31 and valve body 35 it is preferred to form the wall 31 with an air outlet 39 whereby the force necessary to move the valve body 35 is determined solely by the resilience of spring 38.

The operation of the form shown in Figs. 5 and 6 is

similar to that of the first described form and requires only manual pressure upon the collapsible tube 11.

In Figs. 7 and 8, there is shown another slightly modified form of the invention, wherein a cylindrical member 40 is provided adjacent one end with an internally threaded portion 41 and on the other end is formed with a wall 42. Intermediate the ends of cylindrical member 40 is a longitudinally extending slot 43 for a purpose hereinafter described. Slidable longitudinally of and within cylindrical member 40 is a piston 44 and a rod 45 having one end fixedly secured to the piston 44 and the other end extending through and beyond wall 42. On the periphery of piston 44 is a lug or projection 46 which extends into the slot 43. The lug 46 is slidable within slot 43 upon movement of piston 44. A cover 47 extends over wall 42 and surrounds cylindrical member 40 to close slot 43. The cover is fixedly secured to the projecting end of rod 45 and movable therewith. Thus upon movement of piston 44 toward wall 42 the cover 47 and lug 46 will open slot 43 for communication with the interior of tube 11. For urging the cover 47 into closing relation with respect to slot 43, a compression spring 48 is circumposed about rod 45 having one end in engagement with cylinder 44 and having the other end in engagement with wall 42. The form of Fig. 7 responds to manual pressure in the same manner as the above described device.

In Fig. 9 there is illustrated a form of the invention which is adapted for use with collapsible tubes in which the neck is not provided with a threaded portion. The cylindrical member 51 is slidably mounted on the neck 50 and is provided with an aperture 52, which aperture is opened and closed by the neck 50 upon sliding movement of the cylindrical member 51. On one end of cylindrical member 51 is an end wall or closure 53 which may be integral with the cylindrical member or fixedly secured thereto. Secured on the inner face of closure 53, by any suitable means, is an elastic strand 54, which is preferably fabricated of rubber. The other end of elastic strand 54 is secured within the tube 11 and preferably at the bottom thereof, as shown in Fig. 9.

While various changes may be made in the detail construction, it shall be understood that such changes shall be within the spirit and scope of the appended claims.

I claim:

1. A self-sealing cap for a collapsible tube comprising a cylindrical member adapted for threaded engagement at one end with the threaded neck of a collapsible tube, and having a slotted aperture at the other end, resilient

conduit means securely retained within the cylindrical member and having one end thereof registered with the threaded neck to afford communication with the interior of the tube whereby there can be delivery of a substance from the tube through the cylindrical member without engagement with the inner surface thereof, a closure disk for slidable guidance during movement normal to the axis of the tubular member within the slotted aperture, said closure disk having an internal projection engaging the side of the resilient conduit means so as to make said closure disk responsive to the condition of the resilient conduit means and resilient means normally urging said closure disk toward its closing position.

2. A self-sealing cap for a collapsible tube comprising a cylindrical member adapted at one end for engagement with a threaded neck of the collapsible tube and having a circumferential slot at the other end, said cylindrical member having an annular abutment with a recess therein, resilient conduit means securely retained within the recess of the annular abutment in said cylindrical member and having one end thereof registered with the threaded neck to afford communication with the interior of the tube, a closure disk mounted in said slot for slidable movement normal to the cylindrical member axis, said disk having an internal projection engaging the side of the resilient tubular member, and a spring member securely retained in the annular abutment to engage cooperatively the projection on said closure disk to urge the disk into sealing the cylindrical member.
